JEREMIAH H. WHITEHOUSE, OF SPRINGFIELD, MASSACHUSETTS.

CALENDERING MACHINE.

Application filed July 11, 1921. Serial No. 483,742.

To all whom it may concern:

Be it known that I, JEREMIAH H. WHITEHOUSE, citizen of the United States, residing at Springfield, in the county of Hampden 5 and State of Massachusetts, have invented new and useful Improvements in Calendering Machines, of which the following is a specification.

This invention relates to calendering-ma-10 chines, and more particularly to so-called "super-calenders" such as are used in the manufacture of glazed paper.

In machines of the above-named general character, the web of paper to be operated 15 upon is unwound from a supply roll and passed between a series of calender-rolls which impart the desired degree of finish to the surface thereof, after which the web is wound up on a take-up roll. It is desirable 20 that the calender-rolls shall be normally driven at relatively high speeds, but that they shall, nevertheless, be capable of running at relatively low speeds, from time to time, to facilitate the threading operation,— 25

that is, the manual passing of the broken ends of the paper web between the calender-rolls whenever, for any reason, the continuity of the web coming from the supply roll is interrupted.

The principal objects of the present in-30 vention are to provide, in a calendering-machine, an efficient and reliable driving means capable of being adjusted at will to drive the calender-rolls either at relatively low speeds, 35 to facilitate the threading of the paper web therethrough, or at relatively high speeds, during normal operating conditions; to pro-40 vide driving mechanism of this kind adapted to operate with a maximum degree of effi-45 ciency without particular accuracy in the initial adjustment of its parts or the employment of expensive foundations for the mounting of said parts, and which is capable also of pre-50 serving indefinitely its capacity for effec-55 tive operation irrespective of constant vibration incident to the running of the machine; and to provide driving means of the character specified having its parts compactly ar-60 ranged to economize floor space.

With the above objects in view, the invention comprises the construction, arrangement and combinations of parts hereinafter described and particularly pointed out in the appended claims.

The invention will be readily understood 55 by reference to the accompanying drawings illustrating the preferred embodiment there- 60 of, and the following description of the construction therein shown.

In the drawings,—

Fig. 1 is a view, in side elevation, of a portion of a calendering-machine, showing particularly a driving mechanism therefor constructed in accordance with the present invention; and

Fig. 2 is a top plan view of the driving mechanism shown in Fig. 1.

Referring to Fig. 1, the calendering-machine is provided with the usual supply roll 4 and take-up roll 6, these rolls being journaled in bearings in suitable standards 8 rising from the floor. The web of paper to be operated upon, which is indicated at 10, leads from a supply roll 4 and passes to and fro in the usual manner between a series of calender-rolls 12 which, as shown, are arranged in a vertical stack and are journaled in suitable bearings in the frame 14 of the calendering-machine. The several calendering rolls 12 are driven one from the other in the usual manner and the lowermost roll is driven from the driving means now to be described.

The driving means comprising a main or primary driving mechanism for driving the machine at relatively high speed under normal operating conditions, and an auxiliary driving mechanism, coacting with the main driving mechanism for driving the machine during the threading operation. The main driving mechanism normally receives its power from a primary motor 18. The auxiliary driving mechanism, in turn, receives its power from an auxiliary or threading motor 20, the latter being considerably smaller 85 in size and less powerful than the main motor. The two motors 18 and 20 are arranged side by side with their armature shafts parallel to each other and to the calender-rolls 12. These motors may be mounted inde-90 pendently of each other and, as shown, they are secured directly to cross-beams 22 and 24 which are, in turn, secured to the floor at one side of the frame 14.

The main or primary motor 18 is connect-105 ed to drive the calender rolls through transmission devices of the so-called link-belt or silent chain type. To this end, a sprocket-wheel

28 is rigidly secured to one end of the armature-shaft of the motor 18. The sprocket-wheel 28 is adapted to drive a link-belt or silent chain, which is indicated at 30, and 5 which passes over said sprocket-wheel and over a similar sprocket-wheel 32, of greater diameter, which is rigidly secured to the shaft of the lowermost calender-roll 12. The size of the motors 18 and 20 and the diameters of the sprocket-wheels 28 and 32 are such 10 as to give the required rate of rotation to the calender-rolls under normal operating conditions.

The take-up roll 6 is also adapted to be 15 driven from the main motor 18 through silent chain type transmission devices similar to those already described. These devices comprise a sprocket-wheel 34, rigidly secured to the armature-shaft 26, alongside 20 of the sprocket-wheel 28; a sprocket-wheel 36 mounted upon the shaft of the take-up roll, and a link-belt or silent chain 38 which passes over said sprocket-wheels. To insure the maintenance of a constant surface speed 25 of the roll of paper web as the latter winds up on the take-up roll 6, the sprocket-wheel 36 is provided with a hub 40 which is frictionally connected with the shaft of the take-up roll. Any suitable means may be employed 30 for thus frictionally connecting the sprocket-wheel 36 with the shaft of the take-up roll whereby the former will be permitted to slip upon the latter as the roll of paper being wound thereon increases in diameter. 35 The secondary motor 20 is adapted to be operated when the primary motor is inactive, to drive the armature-shaft of said primary motor at relatively low speed and thus to effect the required low speed drive of the 40 calender-rolls for the purpose of facilitating the threading therebetween of the paper web. The secondary motor 20 is connected with the armature-shaft 26 of the primary motor 18 by means of the silent chain type 45 of transmission in the following manner: As best shown in Fig. 2, a small sprocket-wheel 42 is secured to the armature-shaft of the motor 20, and a sprocket-wheel 44, of greater diameter, is mounted upon the armature-shaft 26 of the primary motor. The 50 two sprocket-wheels 42 and 44 are connected by means of a link-belt or silent chain 46.

In order that the parts of the driving mechanism shall be assembled in compact 55 compass for the purpose of economizing floor space, it will be noted that the secondary motor is arranged on the same side of the chain connected therewith as the primary motor. It is pointed out that the arrangement 60 of the two motors in the particular manner shown would be impracticable if, for example, spur-gears were relied upon to transmit the power of the secondary motor, unless one or more idler-gears were employed, in which event an added amount of 65

frictional resistance would be involved in the transmission.

The sprocket-wheel 44 is adapted to be connected with the armature-shaft 26 by means of an overthrow clutch 48. The 70 clutch 48 may be a ratchet clutch of any suitable construction, whereby the sprocket-wheel 44 will be operatively connected with the armature-shaft 26 during such time as said sprocket-wheel is being driven by the 75 secondary motor 20 and whereby, when the primary motor 18 has been put in operation and drives its armature-shaft at a speed greater than that at which it has been driven by the secondary motor 20, the overthrow 80 clutch 48 will become operative to disconnect the sprocket-wheel 44 and the armature-shaft 26. Suitable manually-controlled rheostats (not shown) may be employed for starting and stopping the motors 18 and 20. 85

In operation, whenever it is necessary to thread the paper web through the stack of calender rolls, the machine is driven from the threading motor 20. Through the agency of the chain 46 and the ratchet-clutch 48 the motor 20 operates to drive the armature-shaft 26 of the motor 18 at slow speed, and the rotation of said shaft is transmitted through the chains 30 and 38 to the calender-rolls 12 and the take-up roll 6, respectively. After the threading operation 90 has been accomplished, the circuit controller (not shown) is operated to cut in the circuit for motor 18, and simultaneously cut out the circuit for the motor 20. Motor 18 will 95 then pick up the load and when the speed of the armature-shaft 26 increases, under the influence of the motor 18, the ratchet-clutch 48 becomes operative to automatically disconnect said shaft from the sprocket-wheel 44 and thereafter said shaft is driven by the motor 18 at high speed, and accordingly the calender-rolls and the take-up roll are also 100 driven at high speed.

A driving mechanism constructed and arranged in accordance with the present invention may be installed at a considerably less expense than that necessary for the installation of other types of driving mechanism. This advantage is largely due to the 110 employment of a link-belt or silent chain for transmitting the power from the motors. The saving in the cost of installation of the present driving mechanism is made particularly apparent by comparison with the expense of installation of other forms of driving mechanism, such, for example, as one in which the transmission of power is effected through the medium of intermeshing spur-gears. If a spur gear transmission 115 should be employed, the exercise of extreme care in mounting the motors would be necessary in order that the gears shall be properly aligned and otherwise adjusted to properly intermesh and thus insure a maximum 120 125 130 135

degree of efficiency in operation. In practice, wherever a spur-gear transmission is employed in individual electric driving mechanisms of this general character, it is found necessary, on account of the weight of the motors, to mount them upon solid concrete foundations in order that the proper relative adjustment of the intermeshing gears shall be maintained. No such amount of labor or expense is involved in the mounting of the motors of the present driving mechanism, since the transmission of power is effected by means of link belts or silent chains. Such chains or belts, by reason of their flexibility, will enable the driving mechanism to operate without loss of efficiency, although the sprocket-wheels over which the chains pass may have been more or less inaccurately alined when the driving mechanism was installed or may subsequently become displaced from their adjusted positions. Furthermore, the various parts are of simple and rugged construction and they are compactly arranged in such a manner as to occupy a minimum amount of floor space. As clearly illustrated in Fig. 2, the economy of floor space is largely the result of the arrangement of the secondary motor on the same side of the chain driven thereby as the primary motor, this arrangement being rendered practicable by the use of the silent chain type of transmission herein described.

Having thus described the invention, what is claimed as new is:—

1. A calendering-machine having in combination, a series of calender rolls, a main driving mechanism for driving the calender rolls at relatively high speed during normal operation conditions comprising a main motor and transmission devices of the silent chain type between said motor and one of said rolls, and an auxiliary driving mechanism for coacting with said main driving mechanism when the motor thereof is inactive for driving the machine at relatively slow speed, said mechanism comprising a secondary motor and transmission devices of the silent chain type between the secondary motor and the armature-shaft of the first motor.

2. A calendering-machine having in combination, a series of calender rolls, a take-up roll, a main driving mechanism for driving the calender rolls at relatively high speed during normal operating conditions comprising a main motor and transmission devices of the silent chain type between said motor and one of said rolls, transmission devices of the silent chain type between said motor and the take-up roll, and an auxiliary driving mechanism for coacting with said main driving mechanism when the motor hereof is inactive for driving the machine at relatively slow speed, said mechanism comprising

prising a secondary motor and transmission devices of the silent chain type between the secondary motor and the armature-shaft of the first motor.

3. A calendering-machine having in combination, a series of calender rolls; a main driving mechanism for driving the rolls at a relatively high speed under normal operating conditions comprising, a primary motor, a sprocket-wheel on the armature-shaft of said motor, a second sprocket-wheel on the shaft of one of said calender rolls, and a chain of the silent type passing over said sprocket-wheels; and auxiliary mechanism operative when said motor is inactive for turning said armature-shaft to drive the calender rolls at a relatively low speed, said mechanism comprising a secondary motor, a third sprocket-wheel on the armature-shaft of said motor, a fourth sprocket-wheel on the armature-shaft of the primary motor, and a chain of the silent type passing over the third and fourth sprocket-wheels.

4. A calendering-machine having in combination, a series of calender rolls; a main driving mechanism for driving the rolls at a relatively high speed under normal operating conditions comprising, a primary motor, a sprocket-wheel on the armature-shaft of said motor, a second sprocket-wheel on the shaft of one of said calender rolls, and a chain of the silent type passing over said sprocket-wheels; and auxiliary mechanism operative when said motor is inactive for turning said armature-shaft to drive the calender rolls at a relatively low speed, said mechanism comprising a secondary motor, a third sprocket-wheel on the armature-shaft of said motor, a fourth sprocket-wheel on the armature-shaft of the primary motor, a chain of the silent type passing over the third and fourth sprocket-wheels, and a clutch constructed and arranged to connect the fourth sprocket-wheel with its shaft while said shaft is being driven by the secondary motor and to automatically disconnect said shaft from said fourth sprocket-wheel when driven at a greater speed by the primary motor.

5. A calendering-machine having, in combination, a series of calender rolls, one of which is provided with a sprocket-wheel, a take-up roll carrying a sprocket-wheel, and driving mechanism for the machine comprising a primary motor located at one side of the machine and having its armature-shaft parallel with the calender rolls for driving the rolls at relatively high speed during normal operating conditions, a pair of driving sprocket-wheels on said armature-shaft at the end adjacent the calendering machine, a chain of the silent type connecting one of said pair of sprocket wheels with the sprocket-wheel carried by the take-up roll, a second chain of the silent type connecting

the other of said pair of sprocket-wheels with the sprocket-wheel carried by the calender roll, a driven sprocket-wheel on said armature-shaft at the opposite end thereof 5 from said pair of sprocket-wheels, a secondary motor having a sprocket-wheel on its armature-shaft, a third chain of the silent type connecting the last-mentioned sprocket-wheel with said driven sprocket-wheel for 10 driving the armature-shaft of the primary motor at relatively slow speed when said motor is inactive, the secondary motor being arranged at the same side of said third chain

as the primary motor, and a clutch constructed and arranged to connect said driven 15 sprocket-wheel with the armature-shaft of the primary motor while said shaft is being driven by the secondary motor and to automatically disconnect said shaft from said driven sprocket-wheel when said shaft is 20 driven at accelerated speed by the primary motor.

In testimony whereof I have affixed my signature.

JEREMIAH H. WHITEHOUSE.
